PUNCH PRESS ACTUATED STAKING APPARATUS

Frederick W. Vorreyer, Downers Grove, Ill., assignor to Western Electric Company, Incorporated, New York, N. Y., a corporation of New York

Application June 17, 1943, Serial No. 491,127

2 Claims. (Cl. 113—1)

1

This invention relates to article assembling apparatus and more particularly to a punch press actuated staking apparatus for staking together the parts of a vacuum tube plate assembly.

In the manufacture of vacuum tube plates, which are substantially oval in configuration, and have outstanding flanges along their flattened edges, it has been the practice to use regular staking tools in staking the two halves of the plate together. The usual form of staking tool is provided with two opposite cutting edges and two opposite relatively dull edges which cause a curling over of the stock to effect a crimping of the parts together. In the use of these tools, undesirable projecting fins are formed which interfere with the operation of the tube unless they are flat and when the large and irregularly shaped fins heretofore made are flattened, there is a tendency for them to break off, resulting in a high rate of defective assemblies.

It is an object of the invention to provide a simple apparatus for staking parts together rapidly.

In accordance with one embodiment of the invention, a plate slidable on the bed of the punch press is provided with opposed clamping blocks for clamping two halves of a vacuum tube plate assembly together while the plate is out from under the ram of the punch press and the plate is slidable so that it may be slid under the ram of the punch press which carries a series of cams for tightly clamping the two halves of the vacuum tube plate together and other cams for actuating staking and crimping tools in automatic succession on the downward stroke of the punch press ram. A trip lock is provided which securely locks the slidable plate in proper position beneath the head of the ram until the ram completes its downstroke, whereupon the trip lock is automatically released by a plunger carried by the ram.

A better understanding of the invention may be had by reference to the following detailed description when considered in conjunction with the accompanying drawings, wherein

Fig. 1 is a plan view of the bed of the punch press having fixtures and tools mounted thereon in accordance with the present invention;

Fig. 2 is a view in perspective of a vacuum tube

plate assembled in the apparatus shown in Fig. 1;

Fig. 3 is a plan sectional view showing the clamping mechanism in place under the ram of the punch press and showing the cams on the ram of the punch press in section;

Fig. 4 is an enlarged fragmentary detail view showing the staking tool in position after staking the two halves of the vacuum tube plate together and showing the crimping tool in its retracted position;

Fig. 5 is an enlarged end view of the staking tool;

Fig. 6 is an enlarged fragmentary detail sectional view showing the crimping tool in place after crimping the parts together and the staking tool in its retracted position;

Fig. 7 is a transverse vertical sectional view taken substantially along the line 7—7 of Fig. 3 in the direction of the arrows showing the punch press ram and the cams carried thereby in detail;

Figs. 8 and 9 are vertical sectional views taken substantially along the lines 8—8 and 9—9 of Fig. 7 in the direction of the arrows showing some details of the clamp for holding the two parts of the vacuum tube plate and showing one of the cams in detail; and

Figs. 10 and 11 are enlarged fragmentary sectional views taken substantially along the line 10—10 of Fig. 3 in the direction of the arrows showing the trip lock mechanism in its unlocked and locked positions, respectively.

Referring to the drawings, wherein like reference characters designate the same parts throughout the several views, a vacuum tube plate is shown assembled in Fig. 2. As clearly illustrated in this figure, the plate comprises two similarly shaped halves 12 and 13, each of which is provided with two flanges, the half 12 being provided with flanges 14 and 15 and the half 13 being provided with flanges 16 and 17. These flanges are placed in abutting relation and are to be attached one to another, as shown at 18—18, by a staking operation.

The mechanism for making the assembly shown in Fig. 2 comprises a punch press platen 19 and a punch press ram 20. The ram 20 has suitably secured to it a head plate 21 (Fig. 7) and the platen supports a substantially T-shaped bed

plate 22 (Figs. 1 and 3). As shown in Figs. 1 and 3, the bed plate 22 is provided with ways 23 and 24, in which a clamp supporting plate 25 may be slid from the position shown in Fig. 1, where it is out from under the head plate 21 of the punch press, to the position shown in Fig. 3, where the clamp supporting plate will be under the head plate 21. The clamp supporting plate 25 is provided with a pair of handles 26 and 27, whereby it may be slid from the position shown in Fig. 1 to the position shown in Fig. 3 and vice versa. Suitably fixed to the upper surface of the clamp supporting plate 25 are a pair of guide members 28 and 29 (Figs. 1, 3 and 8) which cooperate with the upper surface of the plate 25 to provide ways in which clamping blocks 30 and 31 are slidably mounted. The clamping blocks 30 and 31 are provided with grooves 32 and 33 for receiving the two halves 12 and 13 of the vacuum tube plate. Positioned in the cavity formed by the grooves 32 and 33 is a central locating block 34, which is fixed to the plate 25 and serves to aid in locating the two halves 12 and 13 of the plate assembly between the clamping blocks. The clamping blocks 30 and 31 are normally urged apart by a pair of compression springs 35 and 36 seated in pockets 37 and 38 and 39 and 40, respectively, in the opposed faces of the blocks 30 and 31. The outward movement of the clamping blocks 30 and 31 is limited by a pair of stop pins 50 and 51, which extend upwardly from the clamp supporting plate 25 and prevent the clamping blocks 30 and 31 from moving beyond the position shown in Fig. 1.

The block 30 is provided with six guide holes 52, in which are slidably mounted six staking pins 53. The staking pins 53 are all locked into a block 54 and the block 54 is slidable in a cut-out 55 formed in the clamping block 31, whereby, when the block 54 is shifted to the right, as viewed in Figs. 1 and 3 and 7, all of the pins 53 will be shifted with it. Encircling each of the pins 53 is a spring 56 seated in a socket 57, one of which is provided for each of the pins 53. In this manner, all of the pins and the block 54 are urged to the position shown in Fig. 1, where the block 54 will be prevented from moving farther to the left by a machine screw 58 threaded into the clamping block 30 and nesting in the block 54. The block 54 is provided with a shouldered aperture 59, which receives the machine screw 58.

The clamping block 31 is of a construction similar to that of the clamping block 30, except that the clamping block 31 supports a plurality of crimping tools 60 fixed to a block 61 and normally urged to the right by compression springs 62. The block 61 is prevented from moving to the right beyond the position shown in Fig. 1 by a machine screw 63, similar to the machine screw 58. The crimping tools 60 are all of exactly the same configuration and are provided with a projecting end portion 64, which enters the aperture formed by the staking pins and which is encircled by an annular shoulder 65. The method of staking and crimping and the tools 53 and 60 are described in detail and claimed in the co-pending application of E. Sirp, filed June 17, 1943, Serial No. 491,128, and it is only necessary here to state that the annular area defined by the end portion 64 and annular shoulder 65 of the crimping tool 60 engages the bent-over flaps formed by the staking tool 53 and crimps them into place in the operation of the present apparatus, as will be described more in detail hereinafter.

Attached to the head plate 21 of the punch press are a pair of cam members 75 and 76 (Figs. 3 and 7) which, when the ram 20 of the punch press is driven downwardly, will slide along the retainer blocks 77 and 78 and will engage a pair of cross heads 79 and 80, respectively, to move the cross heads toward the center of the apparatus. The cross heads 79 and 80 carry actuator pins 81—81 and 82—82 rigidly attached to them. The actuator pins 81 and 82 are adapted to engage the clamping blocks 31 and 30 when the cross heads 79 and 80 are shifted toward the center of the apparatus by the camming members 75 and 76 and in this manner, the two halves 12 and 13 of the vacuum tube plate will be clamped into position between the clamping blocks 30 and 31. Just prior to the operation of the cross heads 79 and 80 under the influence of the cam members 75 and 76, the two halves 12 and 13 of the vacuum tube plate will be pushed firmly against the clamp supporting plate 25 by a spring-pressed plunger 83, the shank 84 of which extends through the head plate 21 of the punch press and is encircled by a compression spring 85, which normally urges the plunger 83 downwardly. Thus, by means of the plunger 83 and the clamping blocks 30 and 31, both actuated by the punch press ram through the head plate 21, the two halves 12 and 13 of the vacuum tube plate will be clamped in position to be staked together.

Mounted on the underside of the head plate 21 is a hinge block 90, in which a pivot pin 91 is mounted (Figs. 7 and 9). The pivot pin 91 pivotally supports a camming member 92, which is normally urged to assume the position shown in full lines in Fig. 9 by a leaf spring 89 attached to the hinge block 90 and bearing against a face of the camming member 92. When the head plate 21 of the punch press is moved downwardly, the camming member 92 will engage a cam surface 93 formed on an actuator block 94, which is slideable with respect to the actuator pins 82 and which is normally urged to the left (Figs. 1 and 3) by contractile springs 95—95 to the position shown in Fig. 1, where its left edge will abut a stop pin 96. The actuator block 94 serves as an abutment for compression springs 97—97 seated in sockets 98—98 formed in the cross head 80. The springs 97—97 urge the cross head 80 to engage a stop pin 99 fixed on the bed plate 22 of the press. The actuator block 94 carries a pair of actuator pins 100—100, which are adapted to engage and actuate the block 54 when the camming member 92 engages the camming surface 93 and actuates the actuator block 94. When this action occurs, the staking pins 53 will be driven through the abutting surfaces of the flanges 14, 15 and 16 to pierce and bend them, as shown most clearly in Figs. 4 and 6. After the piercing of the flanges 14, 15, 16 and 17 is completed, the camming member 92 will strike a cam block 101 (Fig. 9) to rock the camming member 92 against the action of the spring 89 and thereby move the camming member 92 to the position shown in dot and dash lines in Fig. 9, where a cut-out 102 formed therein will register with the camming surface 93, thus permitting the springs 95 to move the actuator block 94 back to the position shown in Fig. 1, to thereby withdraw the staking pins 53 from the holes which they have formed in the flanges 14 and 17.

As soon as the camming member 92 is cammed out of engagement with the surface 93, cam 105, suitably attached to the undersurface of the head plate 21, will engage a camming surface 106 on 76 an actuator block 107 similar to the actuator

block 94. The actuator block 107 carries actuator pins 108-108 (Figs. 1, 3 and 7), which will engage the block 61 and, through the block 61, impart movement to the crimping tools 60. The actuator block 107 is normally urged to the right (Figs. 1 and 3) by contractile springs 109-109 to a position where it will engage a stop pin 110. The actuator block 107 also serves as an abutment for springs 111, which normally urge the cross head 79 to engage a stop pin 112 and in this feature the actuator block 107 serves a purpose similar to that served by the actuator block 94. The actuator blocks 94 and 107 are slideable on the surface of the plate 22, being held in alignment thereon by guide members 113-113 and 114-114, respectively. When the slideable clamp supporting plate 25 is moved to position under the head plate 21, as shown in Fig. 3, the plate 25 will be locked in that position until the very end of the downstroke of the ram 20 and will then be unlocked by a release pin 121 fixed to the underside of the head plate 21. The release pin 121 is positioned to engage a latch member 122 toward the end of the downstroke of the ram 20 to unlock the clamp supporting plate 25 after all of the staking and crimping operations have been completed. The latch member 122 is seated in a tapered aperture 123 formed in a bracket 124 and is normally urged upwardly by a compression spring 125 to the position shown in Fig. 11. The compression spring 125 is seated in a pocket 126 and engages the latching member 122 eccentrically so that when the release pin 121 pushes the latch member 122 downwardly against the action of the spring 125, the latch member 121 will tilt and will catch under the shoulder 127 of a bracket 128 mounted on the rear end of the clamp supporting plate 25. The bracket 128, as seen most clearly in Fig. 3, has a cam surface 129 formed on it, which, when the plate 25 is slid to the position shown in Fig. 3, will engage the latch member 122 and cam it aside to permit it to engage a surface 130 of the shoulder 127, thus to lock the clamp supporting plate 25 in its rearmost position until the release pin 121 engages the latch member 122 and resets the latch member 122 to the position shown in Fig. 10. As shown in Fig. 10, the latch member has its upper surface engaging the lower surface of the shoulder 127 and is held in that position by the spring 125 until the plate 25 is moved forward to disengage the latch member from the bracket 128, at which time the latch member will snap back to the position shown in Fig. 11.

A better understanding of the invention may be had by reference to the following brief description of the mode of operation thereof.

With the slideable plate 25 in the position shown in Fig. 1, the two halves 12 and 13 of the vacuum tube plate assembly may be placed between the clamping blocks 30 and 31 and the plate 25 may be slid to the position shown in Fig. 3 by means of the handles 26 and 27. After the plate 25 has been slid to the position shown in Fig. 3, the ram of the punch press 20 may be driven through one stroke by mechanism (not shown) to completely attach the two halves 12 and 13 together by staking them, as shown at 18. As the ram 20 moves downwardly, the head plate 21 carrying the various cams will, in automatic succession, clamp the halves 12 and 13, pierce the flanges of the halves with the staking pins 53, and then crimp the overturned edges of the perforations by means of the crimping tools 60.

This succession of operations is initiated when the cam members 75 and 76 force the cross heads 79 and 80 toward the center of the apparatus. As the cross heads 79 and 80 move toward the center of the apparatus, they will move the actuator pins 81 and 82 into engagement with the blocks 30 and 31, thereby to compress the springs 35 and 36 and clamp the two halves 12 and 13 tightly together. As soon as the halves of the assembly are in clamped together position, the camming member 92 will become effective to move the actuator block 94 to the left (Figs. 1 and 7). The actuator block 94 will move the pins 100 against the block 54 to which the staking pins 53 are attached and, accordingly, the pins 53 will be driven through the abutting flanges of the two halves 12 and 13. As soon as the pins 53 have pierced the flanges 14, 15, 16 and 17, the camming member 92 will be rocked against the action of the spring 89 due to its engagement with the cam block 101 and the springs 95 will draw the actuator block 94 to the left (Figs. 1 and 7), thereby to permit the springs 56 to withdraw the staking pins 53 from the perforations which they have formed. Just as soon as the pins 53 are withdrawn from the perforations formed in the flanges 14 to 17, cam 105 will engage cam surface 106 on the actuator block 107 to move the actuator pins 108 into engagement with the block 61, thereby to force the crimping tools 60 into engagement with the bent-over edges of the material forced out of the flanges 14 to 17. As soon as this operation is completed, the stroke of the ram 20 will have been completed and the ram 20 will then move upwardly to permit the slideable plate 25 to be moved back to the position shown in Fig. 1. As the head plate 21 moves downwardly, the release pin 121, toward the end of the stroke of the ram 20, engages the latch member 122 to rock it in the tapered aperture 123 until the latch member 121 catches under the shoulder 127 of the bracket 128. This will release the plate 25 so that it may be drawn back to the position shown in Fig. 1, where the assembled vacuum tube plate may be removed from it and two new halves 12 and 13 inserted in place thereof to be assembled.

What is claimed is:

50. 1. An assembling apparatus comprising a press having a bed and a ram, cam members carried by the ram, a clamp and tool supporting plate slideably mounted on the bed of the press, a series of cam slides operated by the cams and movable 55 at right angles to the direction of movement of the slideable plate, and means mounted on the plate for movement by the cam slides for clamping parts together, perforating the parts and clinching the parts in automatic succession, one 60 of said cam members being pivotally mounted on the ram of the press to actuate one of the cam slides, and a cam mounted on the bed of the press to disengage said pivoted cam member from its associated cam slide after a predetermined 65 amount of movement of the ram.
2. An assembling apparatus having a bed and a reciprocating ram, a cam member hinged to the ram, a tool having means for assembling a plurality of parts and having a cam surface positioned to be engaged and actuated by the cam member upon reciprocation of the ram, said tool moving transversely with respect to the ram, a relatively stationary cam supported by the bed and having a camming surface extending substantially transversely with respect to the first

mentioned cam surface for moving the cam member on its hinged connection at a predetermined point in the reciprocation of the ram to disengage the hinged cam member from the tool and thereby render the cam member inoperative to actuate the tool, and means normally tending to return the cam member to operative position.
